AUXILIARY VALVE GEAR FOR LOCO-
MOTIVES

Harry J. Sherrill, Youngstown, Ohio

Application January 2, 1940, Serial No. 311,974

5 Claims. (Cl. 121—163)

This invention relates to an auxiliary valve gear.

The principal object of the invention is the provision of an auxiliary valve gear mechanism capable of varying the movement of the steam valve so that it operates to retard the movement thereof as soon as a volume of steam is supplied to the main cylinder sufficient to drive the piston by its expansive properties and accelerate the movement of the steam valve at the opposite ends of its movement during the time in which the valve moves from lead position to full steam port opening before reaching the cut-off position and also during movement of the valve from the point of release to the end of the stroke.

A still further object of the invention is the provision of an auxiliary valve gear mechanism of simple sturdy construction comprising a relatively few easily assembled parts.

A still further object of the invention is the provision of an auxiliary valve gear mechanism providing definite adjustability between two of its several parts so that the cut-off position of the steam valve may be varied thereby in order to adapt it for freight work wherein a slow cut-off is desirable or for passenger work wherein a fast cut-off is desirable.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a side elevation of a valve gear showing the auxiliary valve gear connected therewith, the various parts of the complete gear represented by their center points.

Figure 2 is an enlarged detail view of the auxiliary valve gear in Figure 1 and shows in detail the mechanism employed in effecting the variable action of the steam valve.

Figure 3 is an end elevation taken on lines 3—3 of Figure 2.

Figure 4 is an enlarged schematic illustration of a portion of the invention shown in Figure 2 and is provided with broken lines indicating approximate quarters of revolution of the pinion gear therein shown.

By referring to the drawing it will be seen that 55

the illustrated embodiment of the invention shows a valve gear for imparting reciprocatory movements to the steam admission and exhaust valve of an engine and only sufficient illustration is given to enable those skilled in this art to readily understand the invention. The valve gear mechanism shown herein can be used in conjunction with any well known valve gear, and is shown in use with the Baker valve gear wherein 10 a bell crank 10 provided with a horizontal arm 11 which derives its movement through a system of links and levers from an eccentric pin 12 of a driven wheel 13 of a locomotive. To the lower end of the vertical arm of the bell crank 10 is pivoted a bell rod 14 which inclines forwardly and upwardly, the forward end being split and pivotally mounted on a pin 15. Pivoted to the forward end of the bell rod on the pin 15 is the upper end of a vertically disposed combination lever 16. Pivotally connected to the lower end of the combination lever 16 there is an adjustable union link 17, the opposite end of which is adjustably pivoted to a crank arm 18 of a crank shaft 19 which is rotatably mounted in an approximately vertically positioned pivot rod 20, the upper end of the pivot rod 20 being pivotally mounted on a stationary pivot 21 which is positioned on a portion of the locomotive frame. The lower end of the pivot rod 20 has pivotally connected thereto a secondary union link 22 which is connected in the usual manner to the main cross head pivot 23 of the engine. The main cross head is connected to the driven wheel 13 of the locomotive by the usual connecting rod 24.

By again referring to the crank shaft 19 and to Figures 2 and 3 of the drawing in particular, it will be seen that the crank arm 18 is provided with a pair of openings therein to either of which the adjustable union link 17 may be pivotally affixed. It will also be seen that the crank shaft 19 extends through the pivot rod 20 and carries a pinion gear 25. A suitable bracket 26 is affixed to the pivot rod 20 and serves to support the innermost end of the crank shaft 19. Still referring to Figures 2 and 3 of the drawing it will be seen that a stationary rack 27 has been provided on which a plurality of gear teeth adapted to mesh with the teeth of the pinion gear 25 are formed. The rack 27 is mounted on the locomotive frame by any suitable means. It will thus be seen that as the locomotive wheel 13 revolves in the direction indicated the system of links and levers connecting the eccentric pin 12 and the pin 15 of the combination lever 16

serves to impart controllable motion to the upper end thereof while the lower end of the combination lever 16 receives movement from a main pivot on the locomotive wheel through the connecting rod 24, the secondary union link 22, the pivot rod 20 and the adjustable union link 17 which is in turn actuated by the crank arm 18 and the pinion gear 25. It will be seen that for purposes of simplicity all but the essential features have been omitted from the drawing and that the simplest form of mechanism is illustrated. It will also be seen that the principal advantage of the mechanism shown and described herein is the ability of varying the movement of the steam valve 28 which is connected through a suitable valve stem cross head rod 29 to a pivot 30 on the combination lever 16 thus movement of the combination lever 16 actuates the steam valve 28 in a desirable manner.

By referring to Figure 4 of the drawing it will be seen that an enlarged view of a portion of the invention including the pinion gear 25 has been shown, and that broken lines divide the pinion gear 25 into approximate quarters with the crank 18 positioned almost vertically as also shown in Figure 2 of the drawing and it will be seen that clockwise revolving motion of the pinion gear resulting from its engagement with the rack 27 will result in the crank 18 traveling through the first quarter, as indicated in Figure 4, during which it will speed up the motion of the lever 17 in relation to that of the lever 20. When the crank is in horizontal position as shown in dotted lines A in Figure 4, the motion imparted the lever 17 will momentarily be the same as that of the lever 20 as the crank 18 swings downwardly through the second quarter of revolution as indicated to assume an approximately perpendicular position. It will be observed that the motion is greatly retarded as the crank 18 is traveling in an opposite direction to that of the lever 20 and that when the crank 18 reaches the lowermost position and corresponds in alignment with the lever 20 the relative movement of the lever 17 will have almost ceased with respect to the lever 20. As the crank 18 subsequently swings upwardly into the third quarter as indicated, the motion is still greatly retarded but increases gradually until the point indicated by the dotted lines designated by the letter B wherein the motion is again the same as that of the lever 20. Passing this point the crank 18 rises vertically through the fourth quarter as indicated during which time the motion is again accelerated as the crank 18 is now overtaking the lever 20 and thus causing acceleration. The reverse occurs when the movement is reversed by the movement of the pinion gear 25 in the opposite direction along the rack 27 as the lever 20 returns to the position indicated in Figure 2 of the drawing. It will thus be obvious that when various component parts of the device are of correct size and spaced in correct positions with respect to one another the result obtained is a rapid movement of the valve 28 in the beginning and end of its stroke and to greatly retard this movement during the middle portion of the stroke. The acceleration causes the valve to open quickly and close quickly as, obviously, motion imparted the valve 28 results in the same motion at both ends of its travel. This movement alternates as the pivot rod 20 swings back and forth and the resulting variation of movement imparted to the lower end of the combination lever 16 results in a direct

advantage in the movement of the steam valve 28. Theoretically there is no retardation or acceleration of the steam valve 28 as it now effects an even travel rather than an uneven travel as in the mechanism formerly used the revolving of the main pivot around the wheel of the locomotive alternately imparted fast and slow motion to the combination lever. The mechanism herein disclosed smoothes out this movement through the use of the pinion gear and rack and crank arm and effects the desirable operation of the steam valve. According to this invention a long dwell followed by a quick cut-off of the valve is effected. This enables the valve to be opened fully quickly and also to close quickly so that the supply and exhaust of steam are not wire-drawn during the period of revolution. In other words, this invention provides an alternate accelerated and retarded movement of the valve during its stroke so as to accomplish a quick and complete opening of the admission port and maintain it up to a point very near the cut-off.

What I claim is:

1. A valve gear mechanism for steam engines having a driven rotatable member, a driven reciprocable member, and a steam admission and exhaust valve, comprising a combination lever, deriving motion at its lower end portion from said reciprocable member and at its upper end portion from said rotatable member, and means including a pivot rod, a pinion gear engaging a rack providing a connection between the said lower end of the combination lever and the said reciprocable member, said means adapted to impart a modified movement to the said combination lever so as to reduce the effective movement of the combination lever during a portion of its travel and to increase the effective movement thereof during another portion of its travel.

2. An auxiliary valve gear mechanism for steam engines having a driven rotatable member, a driven reciprocable member, and a steam admission and exhaust valve, comprising a combination lever deriving motion at its lower end portion from said reciprocable member and at its upper end portion from said rotatable member, a reciprocable cross head for said valve and a rod providing an operative connection between said cross head and the upper end portion of said combination lever, together with means for modifying the movement imparted to the lower end of the combination lever, said means comprising the utilization of a rod pivoted at its upper end, a pinion gear carried on said rod adapted to engage a stationary rack, the bottom of the said pivot rod deriving motion from the said driven reciprocable member and the lower end of the said combination lever deriving motion from the said pinion gear, to modify the effective movement of the said steam valve at predetermined points during the movement thereof.

3. A valve gear mechanism for steam engines having a driven rotatable member, a driven reciprocable member, and a steam admission and exhaust valve, comprising a combination lever deriving motion at its upper end portion from said rotatable member and at its lower end portion from a pinion gear carried on a pivot rod and engaging a stationary rack, the said pivot rod pivoted on a stationary pivot at its upper end and receiving movement at its lower end from the said reciprocable member, a rod connecting the combination lever and the steam valve so that modified movement of the combination lever as im-

parted thereto by the said pinion gear and pivot rods will vary the effective movement of the steam valve so as to increase the same during a portion of its travel and decrease the same during another portion of its travel.

4. A valve gear mechanism for steam engines having a driven rotatable member, a driven reciprocable member, and a steam admission and exhaust valve, comprising a combination lever deriving motion at its upper end portion from said rotatable member and at its lower end portion from said reciprocable member by way of and through a pivot rod pivoted to a stationary pivot at its upper end and receiving movement from the said reciprocable member at its lower end and carrying in rotatable manner a pinion gear engaging a stationary rack positioned adjacent thereto, a crank shaft positioned in said pinion gear and providing means for effecting a connection between a crank arm thereof and the lower end of the said combination lever, together with a rod connecting the said steam valve and the said combination lever so that movement of the said combination lever results in a desirable movement of the said steam valve.

25

5. A valve gear mechanism for steam engines having a driven rotatable member, a driven reciprocable member, and a steam admission and exhaust valve, comprising a combination lever deriving motion at its upper end portion from said rotatable member and at its lower end portion from said reciprocable member by way of and through a pivot rod pivoted to a stationary pivot at its upper end and receiving movement from the said reciprocable member at its lower end and carrying in rotatable manner a pinion gear engaging a stationary rack positioned adjacent thereto, a crank shaft positioned in said pinion gear and providing means for effecting a connection between a crank arm thereof and the lower end of the said combination lever, the said crank arm and the said combination lever provided with two or more pivot locations so that a connecting rod may be adjustably positioned in between them, together with a secondary rod connecting the said steam valve and the said combination lever so that movement of the said combination lever results in a desirable movement of the said steam valve.
